UNITED STATES PATENT OFFICE.

JOSEPH A. SARGERY, OF SHERBROOKE, QUEBEC, CANADA, ASSIGNOR OF ONE-HALF TO
FORREST W. LORD, OF SHERBROOKE, QUEBEC, CANADA.

FOUNTAIN TOOTHBRUSH.

Application filed January 4, 1923, Serial No. 610,659. Renewed February 26, 1926.

To all whom it may concern:

Be it known that I, JOSEPH A. SARGERY, a subject of the King of Great Britain, residing at Sherbrooke, Province of Quebec, Canada, have invented certain new and useful Improvements in Fountain Toothbrushes; and I do hereby declare that the following is a full, clear, and exact description of the invention, such as will enable others skilled in the art to which it appertains to make and use the same.

The present invention pertains to a fountain tooth brush and consists of improvements on Canadian Patent No. 197,488, of February 24th, 1920, and United States Patent No. 1,336,390, of April 6th, 1920.

In these patents, there is provided a brush handle in which is secured a plurality of bristles. The handle is constructed in such a manner as to serve in a fountain brush, and is therefore more expensive than the usual brush handle. When the bristles have become worn it is necessary to discard the entire device. Accordingly, it is an object of this invention to provide a handle adapted to receive a renewable bristle section so that when the bristles are worn a new section may be inserted without necessitating the waste of the handle portion.

The patents also show a tube extending through the back of the brush and into the bristles. This tube remains open when the brush is not in use and thus gives rise to unsanitary results. In this connection, the present invention includes a cap adapted to close the open end of the tube when desired. According to the invention, the tube is made in the form of a hollow screw insertable through the back of the brush. In one side wall of the screw is formed an aperture adapted to register with the feed channel connecting with the reservoir in the brush handle.

Another feature of the invention is a novel supply cartridge adapted for insertion in the brush handle and edge provided with novel sealing means which may readily be removed to enable the flow of cleansing material.

The invention is fully disclosed in the following description and in the accompanying drawings in which:

Figure 1 is a longitudinal section of the device;

Figure 2 is an enlarged longitudinal section through the reservoir;

Figure 3 is an enlarged longitudinal section through the back and bristle section;

Figure 4 is an enlarged section on the line 4—4 of Figure 1;

Figure 5 is a side elevation of the follower mechanism;

Figure 6 is a longitudinal section of the supply cartridge;

Figure 7 is a section on the line 7—7 of Figure 2;

Figure 8 is a perspective view of the bristle section;

Figure 9 is a perspective view of the cartridge;

Figure 10 is an enlarged longitudinal section taken at one end of the cartridge and on the line 10—10 of Figure 11; and Figure 11 is a section on the line 11—11 of Figure 10.

In these views, the numeral 1 indicates a brush handle, the body portion 2 of which is hollow and threaded on an extension 15 of the handle. The handle has a passage way of channel 3 extending from the hollow body to the back 4. The back is provided with laterally curved portions or flanges 5 in which a bristle section 6 is adapted to be inserted. These parts are so constructed that the bristle section will remain tightly in place, but can be readily removed for renewal as required. A hollow screw 7 is passed through the back 4 and section 6 and is provided in its wall with an opening 8 adapted to communicate with the channel 3. The outer end of the screw is externally threaded as at 9 for the reception of a cap 10. This cap is applied when the brush is not in use, thus preventing the flow of material when not required and further maintaining the material in a sanitary condition.

The hollow portion 2 is adapted to receive a cleanser containing cartridge 13 provided at its forward end with an externally threaded nipple 14 receivable within the extension 15 which communicates with the inner end of the channel 3. The opposite end of the cartridge is closed by means of a cap 16 threaded therein and formed with a central aperture 17. This aperture and that in the nipple 14 are closed by means of pivoted flaps 18 of suit-

able flexible material. It will be understood that the cartridge is initially filled by removal of the cap 16 and then closed by the application of the same with the flap 5 covering the aperture.

The hollow portion 2 is internally threaded at its outer end as at 19 for the reception of an externally threaded closure plug 20. A threaded feed screw 21 is held 10 by the plug and adapted to project into the hollow portion 2. The outer end of the screw has fixed thereto a milled disk 22 by means of which it may be manually rotated. The screw is also provided with a 15 collar 23 which rests against the inner face of the plug for retaining the screw in position. A follower 24 is adapted to travel on the screw and is of such circumference as to engage the inner wall of the cartridge. 20 In filling the hollow portion 2, a cartridge 13 is inserted therein, the flaps 18 being previously moved away from the apertures by a pointed instrument. The cap 16 is removed in order that the feed screw may 25 be passed therethrough and the follower 24 applied to the same against the inner face of the cap. The plug 20 is threaded into the outer end of the hollow portion and the device is ready for use in the manner 30 pointed out in connection with the previously patented devices.

While a specific embodiment of the invention has been illustrated and described, it is to be understood that various alterations 35 in the details of construction may be made without departing from the spirit of the invention as indicated by the appended claims.

Having thus fully described the invention, what I claim as new and desire to protect by Letters Patent is:—

1. A fountain tooth brush comprising a handle including a back and a hollow body portion, a bristle section removably inserted in said back, a hollow screw passed through 45 said back and bristle section and having an aperture in a wall thereof, said handle having a channel formed therein connecting said aperture with the hollow body, and a follower slidably mounted in said hollow 50 body.

2. A fountain tooth brush comprising a handle including a back and a hollow body portion, a bristle section removably inserted in said back, a hollow screw passed through 55 said back and bristle section and having an aperture in a wall thereof, said handle having a channel formed therein connecting said aperture with the hollow body, a follower slidably mounted in said hollow body, 60 and a cap adapted to close the outlet end of said hollow screw.

3. A fountain tooth brush comprising a handle including a brush back and a hollow body, said handle having a channel formed 65 therein connecting said hollow body portion with the back, a cartridge disposed within said hollow portion, flaps of flexible material closing outlets in the ends of said cartridge, a feed screw passed into said 70 cartridge through the outer end thereof, and a follower mounted on said feed screw and engaging the inner wall of the cartridge.

In witness whereof I have hereunto set my hand.

JOSEPH A. SARGERY.
